(57) **CLAIM**

The ornamental design for a water cooler cover, as shown and described.

DESCRIPTION

FIG. 1 is an isometric illustration of a water cooler cover of the present invention viewed from a front side.

FIG. 2 is a front view of the water cooler cover.

FIG. 3 is a rear view of the water cooler cover.

FIG. 4 is a right side view of the water cooler cover.

FIG. 5 is a left side view of the water cooler cover.

FIG. 6 is a top view of the water cooler cover.

FIG. 7 is a bottom view of the water cooler cover; and,

FIG. 8 is an isometric illustration of the water cooler cover of the present invention viewed from a rear side.

1 Claim, 5 Drawing Sheets

FIG. 1

FIG. 2

FIG. 3
